Atkinson Holmes
Letters Patent

1191 X

The schedule referred to in these Letters Patent, making part of the
same, containing a description in the words of the said Atkinson Holmes his
self of his machine for carding & spinning wool by one continued operation.

The frame of the machine is $10\frac{1}{2}$ feet in length, $3\frac{1}{2}$ feet in breadth and
two feet 10 inches in height, consisting of two cap pieces, two posts framed
into the caps 2 ft. from the end intended for feeding, 2 ft. 3 inches
long. Two similar posts framed into the caps $5\frac{1}{2}$ ft. still further toward
the finishing end. Two other posts $6\frac{1}{2}$ ft. long framed on to the finishing
end of the caps. Two side railings framed into the short posts parallel
with the caps 1 foot from the lower end: two girts framed into the first
pair of posts, across the frame one directly under the side railing: the other
one inch down from the shoulder: a third girt is framed into the second
pair of posts directly under the other end of the railings. timber, caps & short
posts 6 by 4 inches, side railing, 3 by 6 inches, girts 4 by 6 inches, long
posts 3 by 6 inches, main cylinder, 2 ft 10 inches diameter framed on
standards, 3 inches from the caps, & five feet from the feeder end, an
arch framed into each cap at the ends of the main cylinder, the
circle 1 inch less than the circle of the main cylinder: in which arches
are fixed moving screens & standards for the other cylinders, viz: three
chain rollers two strippers & fancy. The fore cleaner a cylinder of 9 inches
diameter is placed on the caps having an sliding box taken from the
feeders & delivers it to the main cylinder. The first chain roller is next
hung on the arch, & is stripped by the fore cleaner. Then the first stripper
& second chain roller. Then the second stripper & third chain roller working
by pairs. Then the fancy which rakes and clears the wool of knots.
The chain rollers $6\frac{1}{2}$ inches in diameter. The strippers 3 inches, the factors
are $1\frac{1}{2}$ id. diameter roll together, drawing the wool from a rolling
cloth of $2\frac{1}{2}$ ft. in length on rollers of 2 id. diameter driven by a pinion
on the end of the lower. on the same end there is a pinion on the

upper feeder to give it motion. The feeders are driven by a gallows wheel washer or a pinion of 16 cogs on the right hand end of the main shaft the out side of the frame. This turns a wheel of 60 cogs or teeth both cast iron & the largest is 16 diameter. the shaft is hung at the out end by an iron strap turned with square corners, that it may be fastened to the frame & give 8 in room between the strap and the frame, the other end is hung within the frame and a square on the end of the shaft still within for a pulley for moving the chain rollers. a pulley is fixed on the gallows wheel shaft next to the strap of 8 in diameter. on the shank cog is another pulley of 16 in diameter and round there is a leather or strap to give motion. The shank cog and wheel are the same ~~size~~ of the gallows wheel and washer. The wheel is put on the under feeder shaft and the pinion or cog is standing to it on a shank through the caps on the left hand end of the cylinders, there are pulleys on the following shafts, viz: on the main shaft 1 ft. 11 in on the fancy 4 in on the strippers 9 in on the fore clear 10 in and on the crank shaft under the main cylinder 5 ft. 6 in and a leather or strap to run under the main pulley over the stripper pulley, the fore clearer pulley, the crank shaft pulley and the fancy pulley and turn all the pulleys united with it. The doffers are the two last cylinders of the carding part of this machine. These are 9 in. diameter & of equal motion placed one above the other 4 in. apart, and a pulley on the second doffer shaft of 1 ft. 8 in diameter, and is moved by a pulley on the gallows wheel shaft 4 in diameter, a pulley on each doffer shaft of equal size to equalize the motion by a strap. The first doffer is hung on standards from the caps to the standards for the fancy. The second in sliding boxes on the caps. The crank is placed directly under the outside doffers, with a pulley on it of 5 inches diameter, & a pulley on the crank shaft directly back of it 10 in diameter the strap to move it. The bar of the crank as long as the width of of the frame from inside to inside, with a crank at each end, to sweep a circle at each end of 17 1/2 in. then four staves two on each crank, standing up by the doffers for holding the combs, & giving them play that they may stop the doffers of wool. one fourth the length of the staves must be above the combs, which of the shortest is 6 in. and the longest 8 in. The combs are then plates of steel 1 in. wide with 10 teeth to an inch $\frac{1}{2}$ of an inch deep.

fastened to a bar of wood $\frac{3}{4}$ of an inch thick 2*id.* wide. These are fastened with
 screws and nuts to the stakes. For the first doffer the ^{card} is hung to the long-
 est stakes which should be outside. The shortest inside stakes are use for the
 second doffer. at the top of the stakes there are stakes forming right angles
 with joints projecting back to the arches which confine the combs to their place.
 The cards are set in the form of the common carding machine — except the
 doffers, which are set in rows round the cylinder. The strips for the first $\frac{1}{2}$
 of an inch wide. Let one to every two inches. On the second doffer the
 strips are 1*id.* wide and let also to every 2*id.* the spaces on one must agree
 with the cards on the other, that they may take all the wool from the
 main cylinder. Then is placed to each doffer a roller of 1*id.* diameter, with
 deep groves made in them of smooth wood or tin to agree with the strips of
 cards; hung upon standards, & driven by a cord from the doffer cylinder.
 Then to each are two rollers 6*id.* longer than the card cylinder round with
 wire of middling size from end to end, that have motion first, by rolling
 together by a cord from the grooved rollers, second by traversing to & fro, by an
 oval nut on the main shaft, & a chain or strap from the nut drawn over a
 a pully to one end of the roller, and a spring. Their motions are to draw & roll
 the the shivers of wool coming from the rows of cards. They are hung with stakes
 at each end of the rollers projecting forward at right angles 1 ft. long, and
 play on a pin. Then to each doffer there are put dividing rollers two to the
 first and three to the second. The rollers made of tin 2*id.* diameter, and the
 divisions made of circles of tin 2*id.* broad put on to the rollers, &c. as to agree
 with the grooves in the first rollers. Their guides are hung on bars standing in
 an angular form so as to bring the bars into one pair of rollers. Then the
 next are two traversing rollers 4*id.* longer than the cards of the machine 2*id.*
 diameter, round from end to end with wire of a size that 15 times
 round will cover one inch; they are placed in a box with grooves in the
 sides, and cross pieces for sliding in them. They traverse 1*1/2* ft. a pully at each
 end of the box. 4 cards fastened to each cross piece, over the pulleys that they
 may traverse contrary to each other & this motion must be by turns, in
 moving over the length of the box the motion must be divided into ten
 parts, this motion is given by two cast iron cog wheels placed under the

rollers of 1 ft. diameter with cog not quite half round the wheel the wheel must be alike, the cog on the inward side, to turn a pinion between them, of 4 ft. diameter standing upright, with another pinion above it to mesh into a bar fastened to the two under cog pieces, with teeth in one side to agree with the pinion, these pinions turn half the time one way and half the time the other.

By the cogs on the large wheel, being placed on opposite sides, a spur wheel is put on the same shaft of 1 ft. 5 in. diameter with 20 cogs, and a shaft placed on a level with that shaft with a pinion of two teeth, which gives the above mentioned irregular motion. It is driven by a pulley on the last said shaft 1 ft. 5 in. and a pulley on the main shaft of 9 in. These give a slack twist to the rope and draw it along at the same time. The drawing rollers are as follows. 5 fluted iron rollers, 2 $\frac{1}{2}$ feet long 2 $\frac{1}{2}$ in. diameter with a shank for a wheel at one end and only a quidgen at the other: these and the traversing rollers are placed on a board, and the standards are fixed for moving that the draught may be altered according to the length of the wool the maximum 3 $\frac{1}{2}$ ft. On the shank end of the rollers, there are cast iron cog wheels of different sizes to increase the motion of the rollers from the first to the last as follows. 45 $^{\circ}$. 46 $^{\circ}$. 45 $^{\circ}$. 46 $^{\circ}$. The pinions for driving them has 16 teeth & the largest wheel 40 cogs. They are driven by a drum under the frame and pulleys on the shanks of the pinions. The pulleys 5 in. and the drum according to the motion of the driving wheel, the large cogwheel should be 1 ft. diameter. On the top of the iron rollers are short wooden rollers 7 $\frac{1}{2}$ in. long 2 $\frac{1}{2}$ in. diameter fluted and covered with leather, four to each iron roller, they are pressed down by short iron levers fastened at one end and a weight at the other. These levers are confined by bars of iron lying across the rollers, though not touching them, but supported by bars across the frame. The levers are made with spindles 1 ft. 5 in. long 1 ft. round and the rest of it square, excepting a quidgen at the end. It is hung at each end by the shoulders of the square part, a pulley of 1 $\frac{1}{2}$ in. diameter is put on the square, a tin cup or flise of 1 $\frac{1}{4}$ inch diameter, 5 in. long screwed on to the round part of the spindle at the end: and a spool to traverse up and down within the cup. —

The spindles must point towards the last set of rollers, standing in a perpendicular form half above and half below. The thread runs over the cup and

is led from one end to the other of the spool by the traverse motion. This motion is given by a heart wheel near the back end of the machine by the feeders and is driven by a cord from the under feeder shaft & a small pulley of 4 $\frac{1}{2}$ ft diameter to a large pulley on the heart wheel shaft of 2 ft. diameter; then long levers with a crop piece under the heart. The levers are hung two thirds from the heart to the gate. The gate stands between the long posts consisting of two side pieces 5 ft. long for sliding in the grooves prepared for them, with bars across for the ends of the spools to rest upon to give the draught to the thread, and by raising and falling gives the traverse motion. The crop must be 6 ft from the rollers. The spindles are supported by bars across the posts. The drums for driving the spindles, are placed back of the spindles 3 ft. and are one foot diameter and a band from the drum to each whell on the spindles. The drum to each set of spindles lying level which gives a half crop to the bands. No exact rule can be given for the moving parts of the machine as the driving wheel cannot be always alike. The sizes of many of the pulleys may be calculated from the size and motion of the drums they must agree one part with another so as gently to draw and not break the wire. The number of spindles cannot be determined for the card may be longer or shorter as best suits the builder. It is recommended to a 2 ft. card.
